(57)

CLAIM

The ornamental design for a vaporizer device, as shown and described.

DESCRIPTION

FIG. 1 is a top, front, and right side perspective view of a vaporizer device of our design;

FIG. 2 is another top, front, and right side perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The dashed broken lines illustrate portions of the vaporizer device that form no part of the claimed design.
